TONE CONTROL

Ambrose C. Miller, Jenkintown, Pa., assignor to
Philco Radio & Television Corporation, Phil-
adelphia, Pa., a corporation of Delaware

Application May 8, 1936, Serial No. 78,702
In Great Britain May 25, 1935

3 Claims. (Cl. 179—171)

This invention relates to tone control devices for radio receivers by which the tone quality of the reproduced sound may be varied as desired. The principal object of the invention is to provide a circuit for a tone control device of the type having several adjustable positions, which is generally superior to prior circuits of this class and which is a marked improvement by virtue of the elimination of the annoying clicking sound which accompanies adjustment of prior multipoint devices as used.

Generally speaking, a tone control device comprises a group of condensers and switching means arranged so that the condensers may be selectively included or excluded from the receiver circuit. Heretofore, the tone control device has been connected in the plate or anode circuit of an audio-frequency amplifier with one terminal of the device connected to the anode of the amplifier and with the other terminal connected to ground or alternatively to the anode supply circuit. In such arrangements, the condensers of the tone control device are connected directly in circuit with the amplifier tube or with the plate resistor comprising an element of the conventional resistance-capacitance coupling. In either case, the condensers of the tone control device are subject to a charge which has a constant component due to either the voltage drop across the tube or the voltage drop established across the plate resistor by the direct current component of the plate current. In either case, when the tone control device is adjusted from one position to another, one or more of its condensers is suddenly either charged or discharged and this charging and discharging of the condensers causes the undesirable clicking sound.

In accordance with the present invention, the tone control device is located so that it functions efficiently, and at the same time, the objectionable charging and discharging of the condensers is avoided and the undesirable clicking sound is eliminated. The invention may be understood by reference to the simple embodiment illustrated on the accompanying drawing, the single figure of which is a schematic illustration of a portion of a radio receiver embodying the invention.

Referring to the drawing, a conventional vacuum tube V_1 , functioning either as a detector or as an audio-frequency amplifier, is coupled by the conventional resistance-capacitance coupling to an audio-frequency amplifier V_2 . The coupling may comprise a plate resistor R_1 having one extremity connected to the anode of the tube V_1

and its other extremity connected to the anode supply and through a by-pass condenser to ground. A second resistor R_2 , constituting the grid resistor of tube V_2 , may have one extremity connected to the grid of that tube and its other extremity connected to a grid-biasing source. The first-mentioned extremities of these two resistors may be connected through a coupling condenser C_1 .

The tone control device TC may comprise a plurality of condensers, each having one terminal connected to a common point, while the other terminals of the condensers are connected respectively to stationary switch contacts. A movable switch arm may be arranged to engage the stationary contacts, so as to include one of the condensers in circuit or several of them in parallel relation.

In accordance with the invention, the common terminals of the condensers, as above mentioned, may be connected to a point P of the receiver circuit between the coupling condenser C_1 and the grid resistor R_2 . The movable switch arm S of the tone control device may be connected directly to a suitable point of the grid resistor R_2 and may be connected also to ground through an additional condenser C_2 . In the specific embodiment illustrated, the tone control device comprises three condensers C_3 , C_4 , and C_5 connected respectively to stationary contacts 3, 4 and 5 of the group of contacts numbered respectively from 1 to 5. By this arrangement, the switch arm S has four selectable positions, in each of which the arm is bridged across two contacts. In the first position with the switch arm bridged across contacts 1 and 2, the condensers are disconnected from the circuit. In the second position with the switch arm bridged across contacts 2 and 3, C_3 alone is connected in the circuit. In the third position with the switch arm bridged across contacts 3 and 4, the condensers C_3 and C_4 are connected in parallel to the circuit. In the fourth position with the switch arm bridged across contacts 4 and 5, the condensers C_4 and C_5 are connected in parallel to the circuit. It will be understood, of course, that other arrangements of condensers may be used.

Thus, the grid resistor R_2 or a portion thereof may be shunted by a capacitance whose value depends upon the position of the switch arm. Since the grid of the biased amplifier V_2 does not normally draw current, no unidirectional voltage will be developed across the grid resistor R_2 and, therefore, the condensers C_3 , C_4 and C_5 will not be subjected to a unidirectional charging voltage

and will not charge and discharge as the tone control device is adjusted from one position to another. Similarly, the condenser C_2 is prevented from charging and discharging. As the tone control device is isolated from the plate circuit of the tube V_1 by the coupling condenser C_1 , the objectionable charging and discharging of the tone control condensers is completely eliminated, as is also the undesirable clicking noise. It will 10 likewise be noted that the resistance R_2 and condenser C_2 constitute a filter for the grid bias supply.

Although the invention has been illustrated and described with specific reference to a preferred embodiment, it will be understood that modifications or changes are possible without departing from the scope of the invention.

I claim:

1. In a radio receiving system or the like, a 20 space discharge device having an anode, an energizing circuit for said anode including a source of unidirectional potential, signal transfer means including a condenser connected to said anode and to said energizing circuit, a second space 25 discharge device having a control grid and a cathode, means connecting said control grid to said signal transfer means, a grid resistor connected to said control grid, a source of grid-biasing potential connected between said resistor and 30 said cathode so as to bias said grid negatively to prevent flow of unidirectional current thereto during normal operation of said second device, a tone control device comprising a plurality of condensers and switching means for rendering one or more of said condensers effective, means connecting said tone control device directly across at least a portion of said grid resistor to the exclusion of said grid-biasing source, and a condenser connected between said tone control de-

vice and the positive side of said grid-biasing source.

2. In a radio receiving system or the like, a space discharge device having an anode, an energizing circuit for said anode including a source 5 of unidirectional potential, signal transfer means including a condenser connected to said anode and to said energizing circuit, a second space discharge device having a control grid and a cathode, means connecting said control grid to said 10 signal transfer means, a grid resistor connected to said control grid, a source of grid-biasing potential connected between said resistor and said cathode so as to bias said grid negatively to prevent flow of unidirectional current thereto during 15 normal operation of said second device, a tone control device comprising a plurality of condensers and switching means for rendering one or more of said condensers effective, and means connecting said tone control device directly 20 across at least a portion of said grid resistor to the exclusion of said grid-biasing source.

3. In a radio receiving system or the like, a pair of successive vacuum tube stages coupled together by a resistance-capacitance coupling including a series coupling condenser and a shunt resistor connected to the input element of the later vacuum tube stage, a tone control device including a plurality of condensers and switching means for changing the capacity of said device, means connecting one terminal of said device to the common connection of said coupling condenser and said resistor, and means connecting the other terminal of said device to a point on said resistor, whereby said device is prevented from charging or discharging during manipulation of said switching means.

AMBROSE C. MILLER.
